TELEMETRIC APPARATUS

Franklin B. Bristol, Middlebury, Conn., assignor
to The Bristol Company, Waterbury, Conn.,
a corporation of Connecticut

Application January 8, 1941, Serial No. 373,617

5 Claims. (Cl. 177—351)

This invention relates to telemetering systems, and more especially to that class of telemetering systems in which a measurement of a magnitude performed at one station is translated into audible code signals, transmitted over a communication channel of a conventional type, and at a receiving station expressed as a scalar magnitude determined by characteristics of said signals.

In the art of telemetering there is recognized the practice of transmitting over a communication system signals initiated by contacts forming a part of a continuous displacement meter, such as a current meter or anemometer, and, by timing the spacing of these signals as received, determining the rate of flow as measured at the transmitting point. There is also recognized a method whereby a variable magnitude, such as liquid level at a transmitting station, is caused to control the nature of code signals, which, at the receiving station, may be interpreted in terms of said code, thereby providing a discontinuous measure of the desired magnitude.

Both these systems have been developed in forms adaptable to conventional communication systems, such as long-distance telephone lines and exchanges, whereby, by the simple expedient of dialing or otherwise calling a number representing the transmitting station, connection may be made with the signaling apparatus and the desired measurement obtained.

It is an object of this invention to provide means whereby a normally inert automatic signaling apparatus which may be operatively associated with any one of a variety of measuring elements may be made subject to operation by telephone apparatus of conventional types, and, upon the establishment of a communication channel therethrough, caused to operate for a predetermined limited time, sufficient to transmit a number of complete impulse groups or signals, after which operation automatically ceases, and the apparatus is cleared from the line.

A further object of the invention lies in the provision of means by which said impulses as audibly received at the home station may readily be expressed as a continuous scalar representation of the measurement performed at the transmitting station.

A further object of the invention is found in the provision of means whereby, without any modification in electrical circuits or apparatus, the system may be made responsive to two or more simultaneous sets of impulses or signals developed by as many transmitting instruments

and representing a corresponding number of measurable magnitudes, and at the receiving end of the system indicated or recorded as separate and independent measurements.

5 Other features and advantages of the invention will be hereinafter described and claimed.

In the accompanying drawings:

Fig. 1 is a diagrammatic representation of a telemetering system embodying the principles of the invention.

10 Figs. 2 and 3 are representations of a modified form of receiving apparatus therefor.

Fig. 4 represents a further modification of the invention wherein telemetering between two transmitting stations and two corresponding receiving stations may be carried out over a single communication channel.

15 Fig. 5 is a graphic chart which under certain conditions may be expeditiously employed in the interpretation of measurements.

20 In the drawings, Fig. 1 shows the combination of a transmitting instrument 10, a receiving instrument 11 and interconnecting apparatus including a control box 12, an automatic unattended station 13, a conventional telephone exchange 14, an interconnecting circuit or channel 15, and a local circuit 16. At the receiving station is a telephone set 17 of the standard type. The transmitting instrument 10 is here shown as adapted to the purpose of water level determination as measured by the position of a float 18 resting on the surface of a body of water 19 whose level it is desired to determine and transmit quantitatively to the receiving instrument 11. The float 18 is associated with the transmitting instrument 10 through the medium of a cable

25 20 passing over a pulley 21 attached to the instrument and counter-balanced by a weight 22. Secured to the shaft of the pulley 21 is a pinion 23 rotatable with the pulley and meshing with a gear sector 24 mounted upon a rotatable axis or spindle 25. Attached to the spindle 25 is a pointer-arm 26 adapted to deflect through a limited angle with movement of the gear sector 24, whereby the position of said pointer-arm becomes an indication of the liquid level which it is desired to measure. The mechanism of the transmitting instrument 10 may be similar in all respects to that fully set forth and described in U. S. Letters Patent 2,214,159 issued September 10, 1940 to Franklin B. Bristol. In this device a scroll-plate 27 is driven by a motor 28 and caused to rotate about an axis 29 at a constant angular velocity in a counter-clockwise sense as seen in the drawings. The scroll-plate 27 has an

30 35 40 45 50 55

arcuate leading edge and a spiral trailing edge adapted to be engaged by the extremity of the pointer 26, whereby the latter will be displaced in a sense perpendicular to its normal plane of deflection periodically with the rotation of the scroll-plate. Fixed to a shaft 30 journaled for rotation through a limited angle about an axis parallel to the plane of rotation of the scroll-plate 27 is a rocker-plate 31 juxtaposed to the extremity of the pointer-arm 26 in such a manner that, as said pointer is periodically displaced by rotation of the scroll-plate 27, said rocker-plate will be deflected through a short distance causing the shaft 30 to be rotated in a corresponding manner. Carried by the shaft 30 is an arm 32 bearing a member 33 adapted to close or open an electric contact 34 according as to whether the pointer-arm 26 is, or is not, displaced by the scroll-plate 27. By reference to the said Bristol patent it will be seen that the member 33 may thus be used to control a circuit which includes contact 34 in such a manner that there will be imposed on said circuit cyclically recurrent impulses of durations dependent upon the deflection of the pointer-arm 26, and therefore of the position of the float 18.

The control box 12 includes a single-throw, double-pole relay 36, a cam-actuated contactor 37 and a buzzer, howler, or other device, 38 suitable to the production of an audible tone upon energization from a source of electrical power.

The relay 36 is of the double-pole class, arranged when energized to close two independent sets of contacts 39 and 40. The contactor 37 includes two electrically independent contact elements 41 and 42, and a cam member 43 arranged to be driven at a constant speed by a motor 44. The periphery of the cam member 43 is provided with a notch 45, a dwell 46 embracing a large proportion of its circumference, and a short lift 47, these several elements of the periphery operatively engaging a follower 48 whereby the contact elements 41 and 42 will be operated in a sense that when the follower rests in the notch 45 both contacts will be opened, when the follower engages the dwell 46, contacts 41 will be closed and 42 open, and when the follower engages the lift 47 both sets of contacts will be closed. The buzzer or howler 38 may be mounted upon the control box 12, or located within it in such a manner that the sound produced thereby when energized may be distinctly audible outside the box. For purposes of insulation, it is generally expedient that there be included in the control box a small transformer 49 adapted when energized from a commercial A. C. supply source 50 to provide a supply of power suitable to the operation of the several operating circuits of the system, while providing complete isolation between said circuits and the source of supply.

The unattended station 13 is shown diagrammatically in a form greatly simplified in comparison with such stations when in actual use. Here all functions except those desirable for carrying out the functions of the invention, and the apparatus for performing those functions, have been eliminated from the drawings. The station in its simplified form includes a four-pole relay 51, a single-pole low-frequency A. C. relay 52 having in series therewith a capacitor 53, a microphone 54, an audio frequency transformer 55, and such batteries and connections as will now be set forth. The relay 51 serves, when energized, to close four sets of contacts 56, 57, 58 and 59. The relay 52 is of a type adapted to ener-

gization from the "ringing current" commonly used for signalling in telephone circuits, and acts to close contacts 60 when energized. In series with the winding of relay 52 is the capacitor 53 adapted to pass current of ringing frequency to energize the relay but to prevent the flow of direct current through the circuit of said relay. The microphone 54, which is placed in a position where it will pick up sound waves emanating from the buzzer 38 is energized from a battery 62 in series with the primary of the transformer 55 and the contacts 59 on the relay 51.

The internal and interconnecting circuits of the control box 12 and the unattended station 13 are as follows: One terminal of the secondary of the transformer 49 is connected by means of a conductor 63 to a corresponding terminal of the motor 28, the motor 44, the buzzer 38, and one side of the contact 41. The other terminal of the secondary of the transformer 49 is connected by means of a conductor 64 to one side of the energizing winding of the relay 36 and to one side of each of the contacts 39 and 40. The other side of the contact 39 is connected through a conductor 65 to the free terminals of the motors 28 and 44. The free side of the contact 40 is connected by means of a conductor 66 to the contact 34, and thence through a conductor 67 to the free terminal of the buzzer 38. The free terminals of the winding of the relay 36 and the contact 41 respectively are connected together by means of a conductor 68.

The communication channel 15 enters the unattended station 13 as two conductors 69 and 70; and the actuating coil of the relay 52 is connected between these conductors in series with the capacitor 53. Contacts 58 on the relay 51 serve to complete a circuit between the conductors 69 and 70 in series with the secondary winding of the transformer 55. One side of the actuating coil of the relay 51 is connected through a conductor 71 to one side of the contact 60 on relay 52, and the other side of said coil through a conductor 72 to a battery 73, and thence by means of a conductor 74 to the other side of contact 60. One side of contact 56 of relay 51 is connected to the conductor 74, and the other side through a resistor 75 to the conductor 71. Conductors 71 and 72 are also connected to the contacts 42 in the control box. Conductors 63 and 68 are connected to the two sides of contact 57, whereby the latter when closed serves to bridge or short-circuit the contacts 41 in the control box. A telephone set 76 may be connected to the line 15 at the transmitting station, and may be used in the regular way at any time the telemetering apparatus is not in active operation.

The receiving instrument 11 may be of the type fully set forth and disclosed in U. S. Letters Patent No. 2,040,918 issued May 19, 1936, to C. W. Bristol, having a constant-speed motor 78, an actuating magnet 79, and an index or pointer 80 adapted to provide in conjunction with a graduated scale 81 a measure based on the durations of successive cyclical impulses received by the magnet 79. A relay 82 of a type adapted to respond to signals in the local circuit 16 is suitably connected to the telephone 17, and a circuit 83 provides operative connection between said relay and magnet 79. The motor 78 in the receiving instrument is energized from a power source 90 which also may supply the circuit of the magnet 79. A double throw single pole switch 91 provides alternative connection, whereby with the

switch thrown to the left as seen in the drawings, the magnet 79 will be energized through the contacts of the relay 82, and with the switch thrown to the right the magnet will be energized or de-energized according only as to whether said switch is closed or opened.

The operation of the invention as embodied in the form shown in Fig. 1 is as follows: It may first be assumed that the system is inert, and that all parts occupy positions as shown in the drawing; and that it is desired to obtain at the telephone set 17 a signal representative of the height of water represented by the position of the float 18. The operator first dials on the telephone 17 at the receiving station, or otherwise calls through the exchange 14, the number corresponding to the unattended station 13 on the line 15. This will cause a ringing current to flow in the line, which current will pass through the capacitor 53 and operate the relay 52 causing it to close its contacts 60. The closing of the contacts 60 will complete a circuit from the battery 73 through the conductors 71 and 74 and the winding of the relay 51, thus energizing said relay and causing it to close its four sets of contacts. The closing of contacts 56 will serve to bridge the contacts 60 through the resistor 75, so that upon opening of the contacts 60 the relay 51 will remain locked in by current flowing through said resistor, and will not be released upon de-energization of relay 52 due to cessation of the ringing current.

Closing of the contacts 57 on the relay 51 will serve to complete a circuit from the secondary of transformer 49 through conductors 63 and 68 and the energizing coil of relay 36 in the control box, causing said relay to close both its contacts 39 and 40.

Closing of the contacts 39 serves to interconnect the conductors 64 and 65, thus applying the secondary voltage of the transformer 49 to the motors 28 and 44, whereby both these motors are placed in operation. Closing of the contact 40 connects the conductors 64 and 66, whereby the circuit of the buzzer 38 is made complete with exceptions of the contact 34, which is subject to actuation by the member carried by the arm 32. Closing of the contacts 58 in the relay 51 serves to short circuit the conductors 69 and 70, thus providing a complete path for voice currents or the equivalent through the unattended station 13 into the circuit 15. At the same time this action will release the relay 52, and, by means of conventional devices in the exchange 14, will cause the ringing action to cease. Closing of the contacts 59 will provide a complete circuit through the microphone 54, the battery 62 and the primary of the transformer 55, whereby sound waves impinging upon the microphone 54 will cause corresponding currents to flow in the circuit 15.

The scroll-plate 21, driven by the motor 28 will rotate in a counter-clockwise sense and will periodically engage the pointer-arm 26 in a manner, as hereinbefore set forth, to cause the contact member 33 to actuate the contacts 34, applying voltage from the transformer 49 to the buzzer 38, causing the same to emit a succession of audible signals each having a duration depending upon the position of the pointer arm 26. The signals from the buzzer 38 will impinge upon the microphone 54 and will cause a corresponding series of signals to be impressed upon the circuit 15. These signals will pass through the line, and through the exchange 14, and through the local

circuit 16, to the telephone set 17 where they may be heard by the operator listening at the instrument.

There are several alternative ways by which the signals heard in the telephone set 17 may be converted into a definite measurement of the height of water level as determined by the float 18 at the transmitting station: (a) The operator may listen at the telephone and determine the duration of each periodic signal by means of a stop-watch and then by comparison with a graphic chart, such as shown in Fig. 5, may immediately convert the reading into the units which it is desired to measure; and this may be done without the interposition of any further instruments. (b) The operator may manipulate the switch 91, throwing it manually to its right hand position as seen in the drawings each time a signal begins, and opening the switch at the termination of each signal. By this means he impresses upon the magnet 79 of the instrument 11 a series of impulses corresponding to those set up at the transmitting station, and will obtain an indication of the pointer 80 of the dial 81 to represent measured magnitude. (c) The operator may throw the switch 91 to its left hand position and leave it so long as the signals continue to come through the line. Under this condition the relay 82 will be actuated by the currents in the circuit 16 and will perform the function of energizing the magnet 79 in correspondence with the impulses in the line, thus giving the desired indication on the instrument 11.

The cam 43 as driven by the motor 44 in the control box 12, contributes a timing function of a dual nature—limitation of the operating time of the apparatus upon completion of a call to an interval sufficient to enable a satisfactory determination to be made without exceeding the time usually allotted for a long distance call, and the bringing of the various elements of the mechanism to rest in a proper position for the initiation of a subsequent cycle. The motor 44 in the control box, starting coincidently with the motor 28 in the transmitting instrument, rotates the cam 43, which immediately after starting will lift the follower 48 out of the notch 45 onto the dwell 46, thus closing the contacts 41, bridging the contacts 57 in the Unattended Station, and thus locking the relay 36 in its closed position without regard to the position of the relay 51, and assuring that the transmitting apparatus will continue to operate, even though the relay 51 should be released. This accomplishes the function of causing the apparatus when once started to remain in operation until the completion of a cycle. The transmitting instrument continues to operate so long as the follower 48 lies on the dwell 46; and during this interval signals continue to be transmitted through the communication channel, and are available at the receiving station.

While there need be no definite relationship between the speed of the cam 43 and that of the scroll plate 21 in the transmitting instrument, the speed of rotation of said cam would ordinarily be set so that one revolution would be completed in a time approximating 1½ minutes after initiation of the operating cycle. With the scroll plate 21 making one revolution in 15 seconds, which is quite consistent with telemetering systems of this class, there would thus be allowed ample time for at least five complete sets of impulses to be transmitted, which would positively establish the required measurement, and yet be well within the time interval customarily allowed

for long distance telephone calls at the minimum rate. As the cam 43 approaches the completion of a single revolution, the lift 47 will engage the follower 48, causing the contacts 42 to be closed for a short interval of time, momentarily connecting the conductors 71 and 72, and short-circuiting the operating winding of the relay 54, whereby the latter is released and opens all its contacts, the resistor 75 limiting for the moment the current drawn from the battery 73 between the instant when the contact 42 is closed and the instant when the contact 56 is opened. As the cam 43 continues its rotation, the follower 48 will drop from the lift 47 into the notch 45, opening both the contacts 42 and 41. The circuit of the contacts 42 has already been opened by the contact 56. Opening of the contacts 41 serves to release the relay 36, opening in turn the contacts 39 and 40, bringing the motors 28 and 44 to rest, clearing the circuit of the buzzer 38, and causing all elements of the system to revert to their original condition.

In Fig. 2 is shown an alternative method by which impulses of audible frequency may be caused to operate a receiving instrument of the indicating class. A telephone set 95 of the conventional type, adapted for calling and answering in the usual manner, is installed at the receiving station; and a receiving instrument 96, similar in all respects to the instrument 11 in Fig. 1 is arranged to have its actuating magnet energized through a relay 97 subject to currents set up in a microphone 98. With this combination, the transmitting station is called in the usual manner; and as the signals are heard by the operator at the receiving station, he places the telephone sufficiently close to the microphone 98 that the signals will affect the microphone to operate the relay and cause the receiving instrument 96 to provide an indication of the measured quantity.

In Fig. 3 is shown a further alternative which is an improvement on the form shown in Fig. 2 to the extent that it includes means for amplifying sound waves of the selected frequency representing that of the signals which it is desired to utilize, at the same time damping out other sounds which might tend to introduce erroneous results. A receiving instrument 100 is connected in circuit with the relay 101 and a microphone 102 in a manner with the connection of the corresponding parts shown in Fig. 2. A telephone 103 is arranged to produce an audible tone signal in the same manner as that shown in the previous drawings. Between the microphone 102 and the telephone 103 is transposed a resonating chamber 104 tuned to the characteristic frequency of the signal tone. With this arrangement it is found that a material degree of amplification of the desired tone is obtained without any corresponding increase in the volume of other frequencies which may be present in the circuit.

In Fig. 4 is shown an application of the principle illustrated in Fig. 3 to the transmission and measurement of two dependent sets of signals, representing as many dependent measurements. The two systems may be characterized as system A and system B. System A includes a transmitting instrument 105, a control box 106, and an amplifier 107 at the transmitting end, and at the receiving end a receiver 108, a microphone 109 with a relay 110 for rendering the receiver subject to the microphone and a resonator 111.

Similarly, the system B includes a transmitter 112, a control box 113, and a microphone 114.

together with a receiver 115, a microphone 116, a relay 117, and a resonator 118. The microphones 107 and 114 are interconnected and both included in a suitable circuit in an unattended station 119 at the transmitting end of a communication channel 120. Each of the transmitters 105, 112, and associated control box may be the same as transmitter 21 and control box 12 in Fig. 1, and the unattended station 119 may be the same as station 13; it being understood that the control boxes A and B in Fig. 4 may be connected in parallel to the contacts of a relay in station 119 similar to relay 54, and that the microphones 107, 114 may be connected in parallel to a circuit in station 119 similar to that to which microphone 54 is connected in station 13. The buzzer or howler in each of the control boxes 106 and 113 is toned to a characteristic pitch. The communication channel 120 leads through an exchange 121 to a local circuit 122 to which is connected a conventional telephone set at the receiving station. The resonators 111 and 118 are tuned to frequencies corresponding to those of the respective buzzers, so that resonator 111 will tend to amplify a tone of the pitch emanating from control box 106 and resonator 118 a tone of the pitch from box 113. Resonator 111 forming a part of system A is placed between the telephone set 123 and the microphone 109 in such a manner that any tone which it may receive from the telephone will be amplified and impressed upon the microphone. In a similar manner resonator 118 is placed between the telephone 123 and the microphone 116 in such a manner that any tone which it amplifies will be impressed upon said microphone.

The operation of the system in this form is as follows: upon the operator at the receiving station dialing, or otherwise calling the unattended station at the transmitting point, both control boxes 106 and 113 are automatically placed in service and the motors in the transmitting instruments will begin to operate. Each of the transmitters will then define a series of impulses corresponding to the magnitudes respectively measured thereby, and these impulses will be impressed upon the microphones 107 and 114 as sound waves having characteristic tones. These sound waves will be impressed upon the communication channel 120 as electric currents, and, of course may be carried simultaneously in the circuit without mutual interference. The sound emanating from the telephone 123 may then be a combination of the tones developed by the two transmitting instruments, and these tones may come simultaneously or concurrently. This sound being impressed upon the resonators 111 and 118, will by them be resolved into its component tones, so that the microphone 109 will respond only to the signals developed by the transmitter 105. In this way the receiving instruments 108 and 115 will operate without interference to provided measurements of the magnitudes originally determined by the transmitters 105 and 112.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. In a telemetering system for providing at a

receiving station representations of values of a quantity measured at a remote transmitting station, the combination of normally inert means at said transmitting station for measuring an unlimited number of said values within a given range and creating in each of uniform time cycles a continuous audible signal of a duration corresponding to values of said quantity, means for converting said audible signals into electrical impulses corresponding with said quantity values, relay means controlled from said receiving station for bringing said transmitting and converting means into action, means at said receiving station whereby said impulses may be converted into scalar magnitudes representative of said values, and means at said transmitting station for terminating signal transmission at the end of a predetermined time.

2. In a telemetering system for providing at a receiving station representations of values of a quantity measured at a remote transmitting station, the combination of telephonic means at said receiving station and a communication channel extending therefrom, normally inert means at said transmitting station for measuring an unlimited number of said values within a given range and creating in each of uniform time cycles a continuous audible signal of a duration corresponding to values of said quantity, means for converting said audible signals into electrical impulses and impressing the latter upon said channel, relay means for bringing said transmitting and converting means into action, and other relay means responsive to flow of ringing current in said channel for controlling the first-mentioned relay means.

3. In a telemetering system for providing at a receiving station representations of values of a quantity measured at a remote transmitting station, the combination of telephonic means at said receiving station and a communication channel extending therefrom, normally inert means at said transmitting station for measuring an unlimited number of said values within a given range and creating in each of uniform time cycles a continuous audible signal of a duration corresponding to values of said quantity, means for converting said audible signals into electrical impulses and impressing the latter upon said channel, relay means for bringing said transmitting and converting means into action, other relay means responsive to flow of ringing current in said channel for controlling the first-mentioned relay means, and means at said receiving station including a scale and an

index for translating said impulses into representations of said magnitudes by the position of said index with respect to said scale.

- 5 4. In a telemetering system for providing at a receiving station representations of values of a quantity measured at a remote transmitting station, the combination of telephonic means at said receiving station and a communication channel extending therefrom, normally inert means at said transmitting station for creating in each of uniform time cycles an audible signal of a duration corresponding to values of said quantity, means for converting said audible signals into electrical impulses and impressing the latter upon said channel, relay means for bringing said transmitting means into action, second relay means controlling the first-mentioned relay means, third relay means responsive to ringing current in said communication channel for controlling the second relay means, means responsive to energization of the second relay means for maintaining the latter energized despite cessation of said ringing current, and means brought into action substantially concurrently with said transmitting means for maintaining the first relay means energized irrespective of the condition of the second relay means and for thereafter de-energizing both the first and the second mentioned relay means.
- 10 5. In a telemetering system for providing at a receiving station representations of values of a quantity measured at a remote transmitting station, the combination of telephonic means at said receiving station and a communication channel extending therefrom, normally inert means at said transmitting station for measuring an unlimited number of said values within a given range, and creating in each of uniform time cycles a continuous audible signal of a duration corresponding to values of said quantity, means for converting said audible signals into electrical impulses and impressing the latter upon said channel, relay means for bringing said transmitting and converting means into action, timing means brought into action by said relay means for controlling the period of operation of said transmitting means, other relay means responsive to flow of ringing current in said channel for controlling the first-mentioned relay means, and contact means controlled by said timing means for maintaining the latter in operation for a predetermined period despite cessation of said ringing current and for thereafter terminating operation of said timing means.
